METAL DETECTING AND SORTING APPARATUS

Gurdon H. Williams, Haddonfield, N. J., assignor to Radio Corporation of America, a corporation of Delaware.

Application December 23, 1949, Serial No. 134,672

4 Claims. (Cl. 209—71)

1

This invention relates to electrical inspection apparatus and more particularly to the automatic inspection of non-metallic objects for the presence therein of metal.

There has been developed as a roofing material a non-metallic composition material which is light, fireproof and extremely weatherproof. This material is manufactured in box-like slabs of a given size which are laid end to end to form a roof. However, in order for these roofing slabs to have sufficient strength to support a load, it is necessary to reinforce them with a steel wire mesh or lattice. Such roofing material, in a liquid state, is poured around the steel lattice to completely enclose it. This is then baked until hard. The area of the steel lattice is slightly less than that of the enveloping material. In order to prevent insufficiently reinforced slabs from being used it is desirable to automatically inspect the finished slabs for the presence of sufficient steel wire reinforcement on a continuous production line basis. Such inspection apparatus, in view of its use on a production line, is required to be simple in construction and maintenance and its cost must be a minimum.

It is therefore an object of the present invention to provide a system for automatically detecting the extent of metal in a non-metallic body.

It is a further object of the present invention to provide a simple system for automatically detecting the extent of metal in a non-metallic body.

It is still a further object of the present invention to provide an inexpensive system for automatically detecting the extent of metal in a non-metallic body.

These and other objects of the present invention are achieved by using a metal detector in conjunction with a system of relays whereby the signals provided by the metal detector responsive to a first or front portion of the body containing the reinforcing metal and to a last or rear portion of the body containing reinforcing metal are utilized to close a relay which shunts a reject control relay to keep it from rejecting the product when another relay, which in its non-operating condition maintains the reject control relay from rejecting product, is operated by the body passing from under the metal detector. Should the body being inspected not have sufficient metal therein to actuate the metal detector at proper intervals determined by the required extent of the metal in the body, then the shunting relay is not operated and the re-

2

ject control relay is activated to reject the body.

The novel features of the invention, as well as the invention itself, both as to its organization and method of operation, will best be understood from the following description when read in connection with the accompanying drawings, in which,

Figure 1 is a diagrammatic representation of an arrangement of an embodiment of the invention with a conveyor belt, and

Figure 2 is a circuit diagram representative of an embodiment of the invention.

Referring to Figure 1, a conveyor belt 10, driven by a motor 12, carries roofing slabs 14 past a switch SA which is actuated and maintained by contact with a roofing slab 14. The required metal reinforcing mesh 16 is represented by the dotted line in the slab 14. A metal detector 18 is represented by the two rectangular boxes on both sides of the conveyor belt 10. The metal detector electromagnetic field is represented by the arrows between the boxes and is established within an area between the two boxes and normal to the conveyor belt. The switch SA is positioned a distance in advance of the metal detector field slightly less than the desired extent of the metal within the slab, which in the present instance is substantially the length of the slab. Switch SA is therefore released just after the front metal-including portion of the slab has entered the metal-detector field to actuate the metal detector. Switch SB is positioned after the metal detector at a convenient distance from the metal detector field which is less than the length of a roofing slab. The slab must not yet have left the metal detecting field at the time switch SB is activated.

As stated previously the roofing slab 14 being inspected is composed of substantially non-metallic material having a suitable rectangular area and thickness and completely enclosing a reinforcing metal mesh 16 which extends substantially throughout the roofing slab area.

Metal detectors of the type herein employed are well known to the art and essentially include means to establish a balanced metal detecting field and means to detect an unbalance in said field caused by metal moving through it. A pair of field coils excited by an R. F. oscillator may be used to set up a balanced field. These coils may be positioned below and proximal to the conveyor belt and may be contained in the lower box. A detecting coil may be positioned above the conveyor belt and may be contained in the upper box. As long as the metal detecting field

is balanced, a minimum or null voltage is induced in the detecting coil. However, when metal is first moved into the field or when metal is moved out of the field a large unbalance voltage is induced in the detecting coil due to the large changes created in the field by the entering or departing metal. While metal is moving through the entire field area, although the field may be unbalanced, the voltage induced in the detector coil is not as large as the voltage induced when metal is entering or leaving the field since the changes occurring in the field are not as great. A metal detector such as may be used herein is described and claimed in an application by J. H. Reynolds, Serial No. 563,045, for a Metal Detector, filed December 13, 1944, now Patent No. 2,513,745, issued July 4, 1950.

Referring to Figure 2, there may be seen represented diagrammatically three motor driven time delay relays, TA, TB and TC. These relays are of the type wherein the sequence of operation of the contacts is adjustable. Upon excitation of the time delay relay any pairs of contacts may be made to close immediately and upon operation of the relay after the predetermined time delay interval the remaining contacts are closed. Of course, if the time delay relay contacts are set to be normally closed, upon excitation, any desired pairs of contacts may be made to open and, after an elapse of the predetermined time interval, the remaining contacts are opened. Time delay relays of this type are described and claimed in Patent No. 1,794,762, issued to John Albert Garell on March 3, 1931, for "Circuit Controlling Device," Patent No. 2,175,864, for a "Multicircuit Timing Switch," issued October 10, 1939, to Carl Ludwig Anderson, and Patent No. 2,175,865 for a "Timing Switch and Mechanism," issued October 10, 1939, to Carl Ludwig Anderson.

Also represented diagrammatically in Figure 2 are two latching relays LA and LB which are of the well known type which, when they are operated, remained latched and will not release or become non-operative until a current is applied to the respective releasing coils LAR and LBR.

Switch SA is a two-position switch. As the front portion of a slab is carried under switch SA by the conveyor belt, the switch is operated to close contacts SA1. This excites time delay relay TA, and after a time interval, determined by the time it takes the conveyor belt to move the front portion of the slab, which is supposed to have reinforcing metal, from its position when SA is operated to just prior to its entering the field of the metal detector, contacts TA2 are closed.

The output signal of the metal detector is shown being applied to a thyratron 20. This signal, as briefly explained above, is a voltage signal, whose amplitude is greatest upon the entry of metal into the metal detecting field or its departure therefrom. By adjusting the bias applied to the thyratron grid from the variable bias source 22 it is possible to make the thyratron 20 fire only when a leading edge signal and a trailing edge signal is received from the roofing slab 14. The thyratron anode supply is alternating current derived from a transformer 24 and permits deionization of the thyratron 20 almost immediately after a signal is removed from its grid. Included in the thyratron anode circuit is a normally open relay A. Contacts A1 and A2 are closed whenever the thyratron fires responsive to signals from the metal detector.

Therefore, when the front portion of the roof-

ing slab which is supposed to include reinforcing metal arrives under the metal detecting field, contacts A1 and A2 are closed and locking relay LA is operated through contacts A1 and TA2. The closing of contacts LA1 prepares a circuit for the operation of time delay relay TB. When the slab has passed switch SA the switch is returned to a position where contacts SA2 are closed. This energizes time delay relay TB. Contact TB3 is closed immediately. The delay interval between energization and operation of time delay relay TB is determined as the interval required for all but the rear end portion of the slab containing the desired reinforcing metal to be carried out from under the metal detecting field. When contacts SA1 are opened time delay relay TA is rendered inoperative.

Time delay relay contacts TB2 close just prior to the metal detector relay A being operated by a signal received from the rear portion of the slab which contains reinforcing metal. This serves to energize release coil LAR of latching relay LA which is then rendered inoperative. However, relay TB is held operated through its contact TB3 being connected to the power source through normally closed contacts TC2 of time delay relay TC.

Due to its positioning, the leading edge of the slab is carried under and operates switch SB before the metal detector operates responsive to the metal in the rear portion of the slab leaving the metal detector field but after relay LB is operated. Relay TC is energized through the closing of contacts SB1. Contacts TC3 are opened immediately upon such energization. The metal detector relay A is then operated by the signal generated by the metal being in the rear portion of the slab. Latching relay LB is then operated through closed contacts A2 and TB2.

Time delay relay TC has an interval between energization and operation which is determined as the interval between operation of switch SB1 and operation of latching relay LB. Relay D is a reject control relay which is normally held operated through the normally closed contacts TC1 and its own closed contacts D2. Contacts D1, when closed, keep the conveyor motor circuit operating. Should contacts D1 be opened the conveyor motor will stop. Contacts TC1 are shunted or paralleled by contacts LB1 when latching relay LB is operated. Therefore when time delay relay TC is operated and contacts TC1 are opened, if relay LB was previously operated, relay D is maintained closed and the roofing slab is accepted. If relay LB was not previously operated, relay D is opened when contacts TC1 are opened and the conveyor motor circuit is opened. The conveyor belt then stops and the slab 14 is rejected.

Opening of contacts TC2 renders time delay relay TB inoperative. When an accepted slab has been carried past switch SB, the switch contacts SB1 are opened and time delay relay TC is thus rendered inoperative. Its normally closed contacts TC1, 2 and 3 are then closed again. Upon closure contacts TC3 through contacts LB2 energize release coil LBR and relay LB is de-energized. Push button TB is used for the purpose of shunting contacts D2 so that relay D may be closed and the conveyor belt started again after a rejected slab has been removed from under switch SB and relay TC has been rendered inoperative again.

If a slab contains no metal or contains metal which does not extend through the desired in-

spection areas of the slab, then switch SA and relay TA may be operated but since the metal detector signal is absent at the proper time, relays TB and LB will not operate. Therefore the opening contacts of TC1 will open relay D and stop the conveyor belt 10 with the defective slab under switch SB. Time delay relay TC is held energized and the conveyor belt cannot be started again until the removal of the defective slab from under switch SB. If a slab contains reinforcing metal in the front portion and not in the rear portion then switch SA, time delay relay TA, latching relay LA and time delay relay TB are operated but not latching relay LB in view of the absence of the metal detector signal at the proper time. The slab is then rejected.

It has been found that inspection of the designated front and rear areas by the metal detector are all that is required to determine whether or not the reinforcing metal has the proper extent within the roofing slab. Furthermore, it is extremely unlikely that two pieces of tramp metal would be positioned in the precise inspected areas to cause acceptance. The use of this inspection apparatus need not be limited to roofing slabs but can be used in any case where the presence of metal in desired areas of a non-metallic enclosing substance is desired to be inspected.

From the foregoing description it will be readily apparent that I have provided an improved apparatus for automatically and continuously detecting the extent of metal in a non-metallic body. Although a single embodiment of my present invention has been shown and described, it should be apparent that many changes may be made and many other embodiments are possible, all within the spirit and scope of my invention. I therefore desire that the foregoing description shall be taken as illustrative and not as limiting.

What is claimed is.

1. A system for inspecting the extent of metal enclosed in non-metallic bodies being carried on a conveyor belt comprising in combination a metal detector having a balanced metal detecting electromagnetic field through which said conveyor belt carries said bodies, said metal detector including a normally open relay which is operated in response to an unbalance of the metal detecting field caused by the entry of a front portion of one of said bodies having metal therein and in response to an unbalance caused by the departure of a rearward portion of said one of said bodies having metal therein, a reject control switch, first switch means to hold said reject control switch inoperative when said first switch means is inoperative, relay means to couple a circuit in parallel with said first switch means across said reject control switch responsive to operation of said metal detector relay by detection of metal in said body front portion and rear portion, and second switch means to operate said first switch means, said second switch means being positioned to be operated by passage of said body from said metal detector whereby said relay means maintains said reject control switch inoperative when said body contains sufficient metal and said reject control switch is permitted to operate when said body contains insufficient metal.

2. A system for inspecting the extent of metal enclosed in non-metallic bodies being carried on a conveyor belt comprising in combination a metal detector having a balanced metal detecting electromagnetic field through which said

conveyor belt carries said bodies, said metal detector including a normally open relay which is closed in response to an unbalance of said metal detecting field caused by the entry of a front portion of one of said bodies having metal therein and in response to an unbalance caused by the departure of a rearward portion of said one of said bodies having metal therein, a reject control switch, first switch means to hold said reject control switch inoperative when said first switch means is inoperative, second switch means operated in response to the closing of said metal detector relay in response to the entry of said front portion of said one of said bodies into said metal detector field, third switch means operated through said second switch means in response to the closing of said metal detector relay in response to the departure of a rearward portion of said one of said bodies, said third switch means when operated being connected in parallel with said first switch means across said reject control switch, fourth switch means to operate said first switch means, said fourth switch means being positioned to be operated by the passage of said body away from said metal detector, whereby said third switch means maintains said reject control switch inoperative when said body contains sufficient reinforcing metal, and said reject switch is operated to reject said body when said second and third switches are not operated due to said body not containing sufficient metal.

3. A system for inspecting the extent of metal enclosed in non-metallic bodies being carried on a dielectric conveyor belt comprising in combination a metal detector having a balanced metal detecting electromagnetic field through which said conveyor belt carries said bodies, said metal detector including a normally open relay which is closed in response to an unbalance of said metal detecting field caused by the entry of a front portion of one of said bodies having metal therein and in response to an unbalance caused by the departure of a rearward portion of said one of said bodies having metal therein, a two position switch positioned along said conveyor belt in advance of said metal detector field to be operated to a first of its two positions by the passage of a front portion of one of said bodies thereby and returning to a second of its two positions after passage of a rear portion of said body, a first time delay relay energized in response to said two position switch being operated to its first position, the delay interval between energization and operation of said first time delay relay being determined as slightly less than the interval required for said body front portion to arrive at said metal detector field from said two position switch, a first latching relay operated through said operated first time delay relay in response to the closing of said metal detector relay responsive to the entry of a front metal containing portion of said body into said metal detector field, a second time delay relay energized through said latching relay in response to said two position switch being operated to the second of its two positions, the delay interval between energization and operation of said second time delay relay being determined as slightly less than the interval required for said body rear portion to arrive at said metal detector field from said two position switch, a second latching relay operated through said operated second time delay relay in response to the closing of said metal detector relay responsive to the passing of a rear metal containing portion of said body through said metal detector

field, a reject control relay, a third time delay relay connected to said reject control relay to hold it inoperative when said third time delay relay is inoperative, said second latching relay being connected to parallel said third time delay relay connections to said reject control relay when said second locking relay is operated, and a single position switch positioned along said conveyor belt after said metal detector to be operated by the passage of a front portion of said body thereby, said third time delay relay being energized responsive to operation of said single position switch, said third time delay relay interval being determined as the interval required for said body rear portion to pass completely from said metal detector field, whereby operation of said third time delay relay does not operate said reject control relay when sufficient metal is in said body, said second latching relay holding said reject control relay inoperative when said third time delay relay is operated.

4. A system for inspecting the extent of metal enclosed in non-metallic bodies being carried on a dielectric conveyor belt comprising in combination a metal detector having a balanced metal detecting electromagnetic field through which said conveyor belt carries said bodies, said metal detector including a normally open relay which is closed in response to an unbalance of said metal detecting field caused by the entry of a front portion of one of said bodies having metal therein and in response to an unbalance caused by the departure of a rearward portion of said one of said bodies having metal therein, a two position switch positioned along said conveyor belt in advance of said metal detector field to be operated to a first of its two positions by the passage of a front portion of one of said bodies thereby and returning to a second of its two positions after passage of a rear portion of said body, a first time delay relay having normally open contacts, said first time delay relay being energized in response to said two position switch being operated to its first position, the delay interval between energization and operation of said first time delay relay being determined as slightly less than the interval required for said body front portion to arrive at said metal detector field, a first latching relay having normally open contacts, said first latching relay being operated in response to the closing of the contacts of said first time delay relay and said metal detector relay responsive to the entry of a front metal containing portion of said body, a second time delay relay having normally open contacts, said second time delay relay being energized and said first time delay relay being rendered inoperative in response to said two position switch being operated to the second of its two positions, said second time delay relay being of the type wherein one pair of its normally open contacts are closed upon excitation and the other of its nor-

mally open contacts are closed upon operation, said second time delay relay being maintained energized through said one pair of contacts, the delay between energization and operation of said second time delay relay being determined as slightly less than the interval required for said body rear portion to arrive at said metal detector field from said two position switch, said first latching relay being rendered inoperative responsive to the closing of said second time delay relay contacts, a second latching relay having normally open contacts, said second latching relay being operated in response to a closing of the second time delay relay contacts and said metal detector relay contacts responsive to the passing of a rear metal containing portion of said body through said metal detector field, a third time delay relay having normally closed contacts, said third time delay relay being of the type wherein one pair of its contacts are opened upon excitation and the remainder of its contacts are opened upon operation, a single position switch placed along said conveyor belt after said metal detector to be operated by passage thereby of one of said bodies prior to the arrival of a rear portion of said body under said metal detector field, said third time delay relay being excited responsive to operation of said single position switch, the interval between excitation and operation of said third time delay relay being determined as the time required for said body rear portion to pass from said metal detector field, a reject control relay having normally open contacts, said reject control relay being held in an operated position to close its contacts and to maintain said conveyor operating through its closed contacts, said reject control relay being held operating through the normally closed contacts of said third time delay relay, the contacts of said second latching relay when operated serving to parallel said third time delay relay contacts maintaining said reject control circuit operating, passage of said body away from said single position switch rendering said single position switch non-operating, said third time delay relay being rendered non-operating responsive to said single position switch being rendered non-operating, said second latching relay being rendered non-operating responsive to the closing of said one pair of contacts of said third time delay relay.
